UNITED STATES PATENT OFFICE.

DANIEL B. PERKINS, OF PROVIDENCE, RHODE ISLAND.

STROPPI NG DEVICE.

1,243,097.

Specification of Letters Patent. Patented Oct. 16, 1917.

Application filed April 9, 1917. Serial No. 160,645.

To all whom it may concern:

Be it known that I, DANIEL B. PERKINS, a citizen of the United States, residing at Providence, in the county of Providence and 5 State of Rhode Island, have invented certain new and useful Improvements in Stropping Devices, of which the following is a specification.

My invention relates to a device for holding 10 the blades of safety razors while being stropped.

The essential objects of my device are the capacity to operate upon both a double edged blade and a single edged blade; to 15 permit the revolution or reversing of the blade without removing the same from the holder; to afford a feathery contact of the blade with the strop; to insure a uniform contact or pressure of the blade upon the 20 strop; to facilitate the insertion or removal of a blade from the device; and to attain these advantages in a structure simple and inexpensive to construct, and facile to operate.

25 To the above ends essentially my invention consists in such parts and combinations of parts as fall within the scope of the appended claims.

In the accompanying drawings which 30 form a part of this specification

Figures 1 and 2 are front and end elevations respectively of my novel device,

Figs. 3 and 4, similar elevations respectively of the device with the parts distended,

Figs. 5 and 6, top and bottom plan views respectively of the same,

Fig. 7, a longitudinal central section of the device in operative position,

40 Fig. 8, a transverse section on line 8—8 of Fig. 7,

Fig. 9, a longitudinal central section of the device in distended position,

Fig. 10, a transverse section on line 10—10 of Fig. 9,

Fig. 11, a section on line 11—11 of Fig. 9,

Fig. 12, an end elevation of the blade holding member,

50 Figs. 13 and 14, a plan and side elevation respectively of the same, and

Fig. 15, an end elevation of the device shown engaging a portion of a razor strop.

Like reference characters indicate like parts throughout the views.

55 My device in its present and preferred construction consists of a holder comprising

an oblong block or body 16 provided with concave side faces 17, flat ends 18, and a convex or rounded base or bottom face 19. This body is provided in its upper portion 60 with a rectangular, oblong, chamber or recess 20 extending nearly to the ends of the body from the ends of which extend vertical guide openings 21 terminating in the base. The base is preferably slightly recessed as at 22 and in this recess is fixed by a screw 23, at its central portion, a leaf spring 24 with depending free ends. Fixed to the surface of the member 16 at the bottom of the recess or chamber 20 by a screw 26 or 70 otherwise is a metal strip or plate 27 having integral with its ends slightly diverging vertically disposed resilient arms 28 provided with reduced neck portions 29 near their free ends forming finger pieces 30 75 which project above the top of the member 16, and resultant shoulders 31.

Pivotal mounted upon the lower portion of the holder is a frame 32 which, in this instance, comprises two relatively yielding 80 sections similar in all respect, so that a description of one will serve for both. Each section comprises end walls 33 connected by a longitudinally disposed narrow side wall 34. The end walls overlap each other and 85 are provided in their upper overlapping portions with holes 36 registering with each other through which pass pivot pins or screws 38 which enter the end faces of the holder near its bottom and hold the portions 33 in slidable contact with each other thereon. To prevent collapse of the frame sections, a stop pin 40 is located in one side wall 33 at each end of the holder adjacent the free end of the overlapping side wall. 90 The stop pins are held in contact with their respective sections by the downward pressure of flat springs 42 fixed in the holder transversely thereof. The laterally extending free ends of these springs rest on the upper edges of the walls 34. These springs 95 are two in number, located near each end of the holder. In the present instance, these springs are located in transverse channels 44 in the holder having V-shaped central portions as at 45, as shown in Fig. 10, to accommodate intermediate V-shaped bends 46 in the springs to prevent the latter from accidental escape. Mounted in openings 48 in the end walls 33 adjacent the sides 34 are 100 parallel longitudinally disposed bearing rollers 49 in the same horizontal plane, 105

110

adapted to continuously contact with a strop 51.

The support or frame for the blade to be sharpened comprises an oblong plate or yoke 52 provided near its ends with circular openings 53 through which project the finger pieces 30. The necks 29 of the latter rest in the outer margins of the openings in locked position when the arms 28 are distended. That is to say, the shoulders 31 abut against the bottom of plate 52, and the sides of the members 29 above their necks abut against the upper face of the plate. Integral with the ends of the plate or bar 52 are depending legs 54 which pass through the guide openings 21 and terminate in outwardly directed lugs or feet 56. One leg has a central opening 57 above the foot, and the second leg has a similar circular opening 58, from which extends an inclined marginal slot 59. The openings in the legs are to receive the carrier member for the blade to be sharpened, which member comprises an upper plate 60 and lower plate 61 integral with each other at one end and having their other ends free. Near their connected ends each plate has oppositely directed fingers 63; and there are similar fingers 64 near the free ends of the plates. There are also like fingers 65 at the extremities of the plates. The described carrier member, represented in a general way by the reference numeral 66, is removable from the legs. Normally the carrier has its ends extending through the openings 57 and 58 with the lower plate 61 resting on the feet 56. The several lateral fingers serve not only to prevent escape of the member longitudinally, but also afford an increased bearing area upon the blade 67 which is clamped therebetween. In Fig. 12 is shown the angle assumed by the member 66 as it is being passed to its seat in the legs 54, or is being manually rotated to reverse the face of a blade carried therein.

In operating my device, the blade 67 is inserted between the clamping plates 60 and 61 either before or after the member 66 has been introduced into its support, the parts being positioned as shown in Fig. 9. The operator then elevates the frame or support by rearwardly pressing against the feet 56. When the plate 52 in its advance reaches a point to override the shoulders 31 of the arms 28, the latter spring outwardly across their openings 53 and lock the parts in the position shown in Fig. 7. During the described upward movement of the support, the plate 60 contacts with the spring 24 whereby the plates 60 and 61 are clamped upon the blade 67. When the parts have been thus locked in normal or operating position, the holder 16 is grasped by the operator who rests the rollers 49 upon the strop 51 and vibrates the device back and

forth along the strop. Since the holder 16 with which the blade is rigid, is tiltable relatively to the frame 32, it will be noted that when the blade is double edged the bottom bevels of both edges will alternately contact with the strop as the device is vibrated. During this movement, the walls 33 perform the function of guides for the strop. It will be noted by reference to Fig. 15 that when the device is moving in the direction of the arrow and the holder is tilted to the right, the right hand section 70 of the frame 32 yields upwardly slightly. When the device is oppositely tilted and moving in the direction opposite to the arrow, the left hand frame section 75 yields somewhat. The yielding relation of the frame sections makes it possible to attain perfect results even when the strop is inclined. Fairly acceptable results are attained when the sections are non-yielding 80 relatively to each other.

When the lower bevels of a double edged blade have been sharpened as described, the members 29 are compressed by the thumb and finger, whereby the blade support is released, and is downwardly impelled by the pressure of spring 24 into the position shown in Fig. 9. Whereupon the operator grasps the ends 65 of the member 66 and 90 rotates said member 180 degrees without removing the member from its bearings. This reverses the blade. The device is again locked, and the opposite bevels of the blade are next sharpened as already described. 95

Obviously my device will accommodate and sharpen a blade with a single edge, as well as a blade having a double edge.

The holder or block 16 may be any form of frame either solid or otherwise best 105 adapted to carry the operative parts.

Other means of applying the principles of my invention may be employed instead of the one explained, change being made as regards the mechanism herein disclosed, provided the means stated by the appended claims or the equivalent of such stated means, be employed.

I claim:

1. In a stropping device, the combination 115 of a block, a blade carrier on the block, a yieldable frame to which said block is pivoted adjacent the carrier, said block being rigid with the blade carrier and constituting the operating handle, and bearing members on the frame and by contact of which with the strop said frame is relatively fixed.

2. In a stropping device, the combination 120 of a yieldable supporting frame adapted to rest upon a strop, a block pivotally connected therewith, a blade carrier on the block, said block being rigid with the carrier and constituting the operating handle, said block being tiltable relatively to the frame.

3. In a stropping device, the combination 125

of a supporting frame adapted to rest upon a strop, a block pivotally connected therewith, a blade carrier on the block, said block being rigid with the carrier and constituting the operating handle, said block being tilt-
5 able relatively to the frame, said frame being made of independently yieldable sec-
tions.

4. In a stropping device, the combination
10 of a supporting frame adapted to rest upon a strop, a block pivotally connected therewith, a blade carrier on the block, said block being rigid with the carrier and constituting the operating handle, said block being tilt-
15 able relatively to the frame, said frame being made of independently yieldable sec-
tions, said blade carrier being movable relatively to the block.

5. In a stropping device, the combination
20 of a block, a blade carrier mounted upon the block, pairs of diverging plates pivotally embracing the block, and bearing members connecting the free ends of the plates at opposite sides of the carrier.

25 6. In a stropping device, the combination of a block, a blade carrier upon the bottom of the block, a frame comprising pairs of oppositely disposed laterally projecting sec-
30 tions pivotally mounted upon the ends of the block, and bearing members in the sec-
tions.

35 7. In a stropping device, the combination of a block, a blade carrier upon the bottom of the block, a frame comprising pairs of oppo-
35 sitely disposed laterally extending sec-
tions pivotally mounted upon the ends of the block, and yielding arms on the block resting upon the sections.

40 8. In a stropping device, the combination of a block, a blade carrier upon the bottom of the block, a frame comprising pairs of oppo-
45 sitely disposed laterally extending sections pivotally mounted upon the ends of the block, stop pins on one section in the path of the other section, and resilient arms on the block engaging the sections.

45 9. In a stropping device, the combination of a block, a blade carrier mounted upon the bottom of the block, and two oppositely dis-
50 posed frame sections pivotally mounted upon the block and pivotally connected to each other surrounding the carrier.

55 10. In a stropping device, the combination of a block, a blade carrier mounted upon the bottom of the block, oppositely disposed guide plates pivotally mounted upon the ends of the block and extending below the blade carrier, and bearing members upon the plates at opposite sides of the blade car-
60 rier.

65 11. In a stropping device, the combination of a block, a supporting frame slidably mounted in the block, said block being tilt-
ably mounted and constituting the operating handle, and a blade carrier mounted in the

frame and a frame to which said block is pivotated.

12. In a stropping device, the combina-
70 tion of a block, a supporting frame mounted in the block, a blade carrier detachably mounted in the frame, and yielding bearing sections upon the block surrounding the carrier.

13. In a stropping device, the combina-
75 tion of a block, a supporting frame slidably mounted in the block, a blade carrier rotatably mounted in the frame exterior of the block, and a bearing frame upon the block surrounding the carrier.

14. In a stropping device, the combina-
80 tion of a block, a supporting frame slidably mounted in the block and extending below the bottom of the block, a blade carrier comprising resilient superimposed plates mounted in the frame exterior of the block, 85 and a spring upon the block engaging the plates.

15. In a stropping device, the combina-
90 tion of a block provided with a longitudi-
nally disposed recess, and with vertical guideways at the ends of the recess, a frame comprising a cross bar in the recess, and legs on the bar slidable in the guideways ex-
95 tends below the block, a blade carrier mounted in the arms below the block, and means upon the block engaging the bar for locking the frame against movement.

16. In a stropping device, the combina-
100 tion of a block provided with a longitudi-
nally disposed recess, and with vertical guideways at the ends of the recess, a frame comprising a cross bar in the recess, and legs on the bar slidable in the guideways, a blade carrier mounted in the arms, and re-
105 silient locking arms upon the block engag-
ing the bar.

17. In a stropping device, the combina-
110 tion of a block provided with a longitudi-
nal recess, and with guideways, a frame comprising a cross bar provided with spaced openings in the recess, and legs on the bar slidable in the guideways extending below the block, a blade carrier loosely mounted in the arms exterior of the block, diverging compressible arms fixed to the block within the recess extending through the openings in the bar, and shoulders on the arms support-
115 ing the bar.

18. In a stropping device, the combina-
120 tion of a block, a supporting frame slidably mounted in the block comprising a cross bar, and vertical legs upon the cross bar nor-
mally extending below the block, both legs being provided with openings near the bot-
tom, and one leg being provided with an open slot extending to the opening, a blade carrier comprising flat plates connected with each other at one end only mounted in the openings, and a spring upon the block intermediate the blade carrier and the block. 130

19. In a stropping device, the combination of a block, a supporting frame slidably mounted in the block comprising legs, outwardly turned lugs upon the legs exterior of the block, said legs being provided with openings exterior of the block, a blade carrier comprising resilient plates connected at one end and pivotally mounted in the legs, a spring upon the block adapted to contact 10 with the carrier, and means in the block engaging the frame for clamping the carrier against the spring.

20. In a stropping device, the combination of a block, a supporting frame slidably mounted in the block comprising a cross

bar, vertical legs upon the cross bar normally extending below the block, both legs being provided with openings near the bottom, a blade carrier comprising superposed oblong plates connected to each other at 20 one end resting loosely in the openings, lateral lugs upon the plates near their connected ends adjacent one of the legs, lateral lugs near the free ends of the plates adjacent the second leg, and lateral finger pieces upon the 25 free ends of the plates at the opposite side of the last mentioned leg.

In testimony whereof I have affixed my signature.

DANIEL B. PERKINS.
